(57) **CLAIM**

The ornamental design for a combined plant lamp head, stem and stem tip, as shown and described.

DESCRIPTION

FIG. 1 is a front perspective view of a combined plant lamp head, stem and stem tip showing my new design;

FIG. 2 is a front elevation view thereof;

FIG. 3 is a rear elevation thereof;

FIG. 4 is a right side view thereof;

FIG. 5 is a left side view thereof;

FIG. 6 is a top plan view thereof;

FIG. 7 is a bottom plan view thereof; and,

FIG. 8 is a rear perspective view thereof.

No claim is made to the area between the break lines in the stem portion, and the broken line disclosure represents portions of the article in which the claim is embodied, but form no part of the claimed design.
